A MIGHTY MARK OF PUBLIC APPRECIATION.

Some Facts about the

NEWS OF THE WORLD

THE GREAT NATIONAL WEEKLY PAPER.

It gathers its news through thousands of correspondents from the ends of the earth.

It sells well over three million copies each week.

Each issue requires 450 tons of white paper,
15,500 pounds of ink,
60 miles of string.

It is printed on a plant of 26 giant presses, each of which is capable of printing up to 36,000 perfected copies per hour.

It requires the productive labour of about 1,000 men.

The paper used each week would make a line over 8,000 miles long, reaching from London to Toronto in Canada AND BACK again.

These papers packed in parcels make a line 7 miles long.

Over a hundred loads are conveyed by the vans to the stations.

It is estimated that 40,000 newsagents distribute this stupendous product. They are happy in delivering a paper which always pleases.

Your newsagent assists in the greatest and quickest transport transaction of all the ages. The "News of the World" is produced and delivered to you in less time than the Post Office can deliver a letter.

UNITED STATES PATENT OFFICE.

REGINALD BEZZANT, OF LONDON, ENGLAND.

PUZZLE.

Application filed December 9, 1924, Serial No. 754,835, and in Great Britain October 7, 1924.

This invention relates to puzzles and has for its object to provide an improved form of puzzle block requiring the rearrangement after division into geometrically similar submultiples which have to be placed side by side in the requisite correlation to give the solution to the puzzle.

The improved form of puzzle provided in accordance with this invention is a double solution puzzle and comprises a block or sheet intended to be divided into geometrically similar submultiples, one side of the sheet bearing a numerical puzzle and the other a design puzzle, these two puzzles being such that after the block has been subdivided and the submultiple portion correctly rearranged, the solved arrangement of the puzzles appears simultaneously on both sides.

20 The accompanying drawings illustrate a form of the invention in which a numerical puzzle appears on one side of the block or sheet and a pictorial puzzle appears on the other side.

25 In these drawings:

Fig. 1 represents the front side of a puzzle block or sheet in accordance with the present invention.

Fig. 2 represents the rear side thereof.

30 Fig. 3 represents the front side after it has been cut up into small squares and the squares have been rearranged to solve the front puzzle.

Fig. 4 represents the rear side corresponding to Fig. 3.

In the form shown, the front portion of the block or sheet, which may be of cardboard, or of any other material, is printed

into squares and each square has on each side a number. The rear of the block has 40 a printed advertisement or announcement in patchwork or incongruous form. To solve the puzzle the block or sheet is first divided up into squares and the squares have to be so arranged that on the front all the 45 adjacent numbers add up to ten and on the rear the announcement will "read".

The block or sheet may have the requisite working printed thereon or it may be embossed or otherwise formed and the division 50 may be made by cutting or the blocks may be provided with lines of weakness so that they may be readily broken into the requisite submultiple parts.

It will be noticed that in the form of 55 puzzle shown the front portion before division contains a number of independently clear or legible designs while the design on the back is random or incongruous.

I claim:—

A double solution puzzle, comprising a block of material marked on one face for sub-division into geometrically similar submultiples, said block having a numerical 65 puzzle in unsolved arrangement on one face and a design puzzle in unsolved arrangements upon the other face, the respective puzzles being so relatively disposed on the respective faces that when the block is divided into geometrically similar submultiples, and such submultiples are correctly arranged 70 to solve the puzzle on one face, such arrangement correspondingly solves the puzzle upon the other face.

In testimony whereof I affix my signature.
REGINALD BEZZANT.
